[57] CLAIM

The ornamental design for a safety chair for a child for use in motor vehicles, substantially as shown.

DESCRIPTION

FIG. 1 is a front elevational view of a safety chair for a child for use in motor vehicles showing our new design;

FIG. 2 is a plan view thereof;

FIG. 3 is a left side view thereof;

FIG. 4 is a right side view thereof;

FIG. 5 is a rear elevational view;

FIG. 6 is a bottom view; and

FIG. 7 is a front perspective view of the chair on an enlarged scale.
